UNITED STATES PATENT OFFICE.

CEPHAS B. ROGERS AND RUSSELL H. BURR, OF MERIDEN, CONNECTICUT,
ASSIGNORS TO C. ROGERS & BROS., OF SAME PLACE.

DESIGN FOR A COFFIN ORNAMENT.

SPECIFICATION forming part of Design No. 16,411, dated December 8, 1885.

Application filed October 19, 1885. Serial No. 180,358. Term of patent 14 years.

To all whom it may concern:

Be it known that we, CEPHAS B. ROGERS and RUSSELL H. BURR, of Meriden, in the county of New Haven and State of Connecticut, have invented a new Design for a Coffin Ornament; and we do hereby declare the following, when taken in connection with accompanying drawing and the letters of reference marked thereon, to be a full, clear, and exact description of the same, and which said drawing constitutes part of this specification, and represents a face view.

This invention relates to a design for coffin ornament, with special reference to a handle-socket, though it may be used as an ornament independent of the handle; and the design consists in the configuration and ornamentation as hereinafter described, and shown in the accompanying illustration.

The body A of the socket represents a sheaf

of grain. At each side there appears a flap, B, represented as turned over onto the front from the rear, and so as to lap onto the sheaf on the body, as shown in the accompanying illustration, these side flaps constituting the essential characteristic of our design, the representation of a sheaf of wheat without such side parts being well known as an ornament.

We claim—

The herein described design for coffin-trim- 30
ming, consisting in the representation of a sheaf of grain, with a flap, B, at each side, represented as turned over onto the front from the rear, and as shown in the accompanying illustration.

CEPHAS B. ROGERS.
RUSSELL H. BURR.
